UNITED STATES PATENT OFFICE

111,181

DESIGN FOR A DRESS

Maurice B. Green, Spring Valley, N. Y.

Application July 26, 1938, Serial No. 78,741

Term of patent 3½ years

To all whom it may concern:

Be it known that I, Maurice B. Green, a citizen of the United States, residing at Spring Valley, in the county of Rockland and State of New York, have invented a new, original, and ornamental Design for a Dress, of which the following is a specification, reference being had to the accompanying drawing, forming part thereof, wherein—

I claim:

The ornamental design for a dress, substantially as shown.

MAURICE B. GREEN.
